REINHOLD H. WAPPLER, OF NEW YORK, N. Y., ASSIGNOR TO WAPPLER ELECTRIC MANUFACTURING COMPANY, OF NEW YORK, N. Y.

ELECTRIC SPARK-GAP.

1,075,075.

Specification of Letters Patent.

Patented Oct. 7, 1913.

Application filed March 12, 1913. Serial No. 753,698.

To all whom it may concern:

Be it known that I, REINHOLD H. WAPPLER, a citizen of the United States, residing at New York city, county and State of New York, have invented a new and Improved Electric Spark-Gap, of which the following is a specification.

This invention relates to an electric spark gap composed of a plurality of sparking cells which are constructed in a novel manner and permit a ready regulation of the spark to any length desired, even below the length obtained when using but a single cell.

The spark gap is so constructed that it may be readily assembled and taken apart and comprises various novel features of construction more fully pointed out in the appended specification and claims.

In the accompanying drawing: Figure 1 is a front view of a spark gap embodying my invention; Fig. 2 a right hand end view thereof; Fig. 3 a vertical cross section on line 3—3, Fig. 1, and Fig. 4 an enlarged vertical section on line 4—4, Fig. 2, partly in view and partly broken away.

My improved spark gap which is adapted to be used in conjunction with means for generating high frequency electric current of high voltage, is composed of a pair of horizontally extending spaced plates 10, each of said plates carrying at its ends, sockets 11, secured to the plates by screws 12. Within the opposed sockets 11 are securely fitted insulating rods 13 which are preferably made of glass. To plates 10 are soldered or otherwise secured vertically disposed bars 14, the lower ends of which are firmly connected by an insulating rod 15, secured in position by screws 16, while the upper ends of bars 14 carry outwardly extending bolts 17 which may be clamped to the usual binding posts 18 projecting forward from the therapeutic or other machine to which the spark gap is to be coupled.

Between rods 13, 13, 15 is received a plurality of sparking cells, each of which is composed of a pair of opposed cup-shaped members 19. The members of each cell are spaced from each other by means of insulating circular disks 20 which are preferably composed of mica. Within each cup 19, is centrally disposed a conductive stud or projection 21, the free flat end of which extends flush with the edge 22 of the cup. Each disk 20 is provided with a central perfora-

tion 23, the diameter of which exceeds the diameter of stud 21.

Intermediate the adjacent cups of each pair of sparking cells is arranged a squared disk or plate 24 also made of conductive material. For holding these parts together, the studs 21 are provided with threaded bores 25 that engage screws 26 fitted into corresponding aligned perforations of each disk 24 and into the cup-shaped members 19 of the adjacent cells. In this way, a plurality of units is formed, each being composed of a squared disk 24 and a pair of members 19 secured to and extending outward from the sides of said disk. Disks 24 are made of a size to be snugly received between rods 13 and to rest on rod 15. The outer members 19 of the flanking cells are secured to disks 24 by means of screws 26 that engage the studs 21 of said outer members and outer oblong reinforcing blocks 27. The latter are engaged by central screws 28 and lateral screws 29, of which screws 28 are tapped into plates 10 and bars 14, while screws 29 are tapped into plates 10 only. By properly tightening said screws, the cell units 19, 24, 19 and the intermediate mica disks 20 are securely held in position.

When high tensioned current is applied to bolts 17, sparks will be formed between the opposed studs 21 of each cell, the number of cells and the thickness of the mica disks 20 determining the combined spark length. By extending disks 20 comparatively far into the cells and providing them with a central opening 23 only, the sparks are bound to be formed intermediate studs 21, which operation will prevail even after protracted use and after a corresponding heating of the cells, any passage of current between the opposed rims of cups 19 being prevented by the inwardly extending mica disks 20.

For regulating the spark length, any selected number of cells may be short-circuited, for which purpose disks 24 are perforated as at 30, in proximity to the upper corners of such disks. Each row of aligned perforations is adapted to be engaged by a short-circuiting rod 31 having insulated handle 32. By inserting rod 31 into one of the bores of the flanking disks 24 and projecting it to a greater or less extent through the bores of adjoining disks, a corresponding number of cells will be short-circuited,

so that the spark length may be regulated at will.

One of the flanking disks 24 carries a contact 33 preferably made of silver and secured to said plate by a screw 34. This contact is arranged in axial alinement with one row of perforations 30, so that by introducing rod 31 from the other end of the device, all of the sparking cells may be rendered inoperative, and a spark may be formed intermediate contact 33 and rod 31, the length of which is less than the thickness of one mica disk 20.

It will be seen that by my construction, a spark gap is obtained which is reliable in operation even after having become heated owing to protracted use. It further permits a regulation of the spark length within the widest range, whereby the spark length may be reduced below that of a single cell. Finally the spark gap is so constructed that its constituent parts may be readily assembled and taken apart, and that the combined spark length may be adjusted at will by correspondingly varying the thickness of the insulating disks 20 arranged between the cell units.

I claim:

1. An electric spark gap composed of a plurality of sparking cell-units, each unit comprising a disk and a pair of outwardly opening cup-shaped members secured thereto, mutually opposed projections arranged centrally within said members, and centrally

perforated insulating disks intermediate 35 the cell-units.

2. An electric spark gap composed of a plurality of sparking cell-units, each unit comprising perforated conductive disks and a pair of outwardly extending cup-shaped members secured to said conductive disks, mutually opposed projections arranged centrally within said members, centrally perforated insulating disks intermediate the cell-units, and a short-circuiting rod adapted 45 to engage the perforations of the conductive disks.

3. An electric sparking gap composed of a pair of conductive flanking disks, one of which is perforated, an inwardly extending contact on the other disk arranged opposite the perforations of the other disk, perforated conductive intermediate disks arranged between the flanking disks, cup-shaped members secured to both sides of the 55 intermediate disks, inwardly extending cup-shaped members secured to the flanking disks, mutually opposed projections within the cups, perforated insulating disks intermediate the open ends of said members, and a short-circuiting rod adapted to engage the 60 perforations of the conductive disks and the contact.

REINHOLD H. WAPPLER.
